a corporation of New York

Application September 9, 1932, Serial No. 632,283

14 Claims. (Cl. 70—74)

This invention relates to locks. It is particularly directed to a device for locking a door, having a plurality of bolts operable by a single operation for locking or unlocking the same.

5 An object of this invention is to provide in a lock of the character described, a casing attachable to a door, and bolts projecting therefrom for engaging keepers on the floor and on the door jamb, the construction being such that 10 all of the bolts may be readily projected by a turn of a knob or a turn of a key and without application of excessive force.

Another object of this invention is to provide a compact, strong and rugged lock of the character described, which shall comprise comparatively few and simple parts, which shall be inexpensive to manufacture, smooth and positive in operation and yet practical and efficient to a high degree in use.

20 Certain features shown and described in this application are shown, described and claimed in our co-pending application Serial No. 606,499, filed April 20th, 1932.

Other objects of this invention will in part be 25 obvious and in part hereinafter pointed out.

The invention accordingly consists in the features of construction, combinations of elements and arrangement of parts which will be exemplified in the construction hereinafter described 30 and of which the scope of application will be indicated in the following claims.

In the accompanying drawings, in which is shown one of the various possible embodiments of this invention,

35 Fig. 1 is a front elevational view of a lock embodying the invention applied to a door, with parts in cross-section;

Fig. 2 is a side elevational view of the lock shown in Fig. 1 with parts broken away to show 40 the interior construction;

Fig. 3 is a cross-sectional view taken on line 3—3 of Fig. 2;

Fig. 4 is an enlarged partial view of the lock embodying the invention with the rear cover 45 plate of the lock casing removed;

Fig. 5 is a view similar to Fig. 4 but showing the parts in another position;

Fig. 6 is a cross-sectional view taken on line 6—6 of Fig. 5;

50 Fig. 7 is a cross-sectional view of a portion of the door showing the location plate forming part of the lock attached to said door; and

Fig. 8 is a top plan view of said plate.

Referring now in detail to the drawings, 10 55 designates a door adapted to be secured to the

door jamb 11 and the floor 12 by a lock 13, embodying the invention. The lock 13 comprises a casing 14 from which there projects a bar bolt 16 adapted to engage within a keeper 17 in the floor and which is provided with a pivoted strut 5 bar or bolt 19 adapted to engage in keeper 20 in said floor. There further projects from the casing a horizontal bolt 21 adapted to engage within a keeper 22 mounted on the door jamb 11, and a U-shaped bolt 25 likewise adapted to engage the keeper 22.

The casing 14 comprises a front wall 27, a top wall 28, a bottom wall 29, an end wall 30 remote from the edge of the door 10 and an end wall 31 adjacent to and preferably flush with the 15 edge of said door. The rear of the casing may be closed by a cover plate 32 resting on a ledge formed around the rear edge of the casing and screwed thereto by means of screws 33.

The inner surface of the front wall 27 is 20 formed with a pair of parallel guide walls for slidably receiving the horizontal bolt 21 which projects through an opening 34 in the front wall 31. Said horizontal bolt may be constructed substantially as shown and described in our said 25 co-pending application and comprises a portion 35 projecting toward the rear of the casing and provided with a pair of spaced symmetrically disposed pins 36 and 37. The bolt is further provided, for the purpose appearing hereinafter, 30 with a pair of parallel, aligned rack portions 38 adjacent the upper and lower edges thereof.

Slidably mounted on said bolt 21 for reciprocatory movement in a direction transverse to the direction of movement of said bolt, is a member 35 39 shown and described in detail in our said co-pending application and adapted to be reciprocated either by the hand knob 40 mounted on the front wall of the casing or by the key actuated mechanism 41 having an arm 42 engaging a 40 portion 43 of said member. The top and bottom walls 28 and 29 of the casing are provided with aligned, parallel tubular openings 46 and 47, respectively, and slidably mounted in the tubular portion 46 is the U-shaped bolt 25 made of two 45 parts, 50 and 51 and likewise described in detail in our said co-pending application. The part 50 is slidably mounted within said opening 46 and rotatably receives the cylindrical stem portion 52 of the part 51. Said stem portion 52 50 is provided with a pinion 53 adapted in one position of the bolt 25 to coat with the teeth of the ratchet 38, for the purpose hereinafter appearing. The member 51 is further provided with a square shaped portion 53a aligned with 55

the stem 52, with a horizontal portion 54, and with an arm portion 55 parallel to the portion 53 and adapted to cooperate with the keeper 22.

For the purpose hereinafter stated, the rear 5 cover plate 32 is provided with a pair of inwardly extending, symmetrically disposed and vertically aligned pins 57 and 58. Pivoted to the pin 57 is one end of a flat plate 59 substantially lying against the inner surface of said cover 10 plate 32 and having a slot 60 receiving the pin 36 therethrough. Said plate 59 is formed with a small slot 63 adjacent the opposite end thereof, receiving a pin 64 fixed to the slidable portion 50 of the U-shaped bolt 25.

15 It will now be understood that as the knob 40 or the arm 42 is rotated, the member 39 will be reciprocated with respect to the horizontal bolt 21 and will cause reciprocation of said bolt. Movement of the bolt 21 will cause pivotal movement of the plate 59 for causing reciprocation of the bolt 25. The plate 59 is preferably constructed and shaped substantially as shown and described in our co-pending application, and the slot 60 is so shaped that upon projecting the 20 bolt 21 the U-shaped bolt 25 will move upwardly from the position shown in Fig. 4 until the square shaped portion 53a of the bolt part 51 moves out of the square shaped slot 46. Further projecting movement of the horizontal bolt will 25 cause the bolt part 51 to be rotated from the position shown in Fig. 4 through an angle of 180° by reason of engagement of the rack teeth 38 with the teeth of the pinion 53. Continued projecting movement of the horizontal bolt will 30 cause the bolt 25 to be moved inwardly toward the horizontal mid-section of the casing so that the portion 55 thereof will engage the keeper 22.

Means is provided for projecting the bolt 16 simultaneously with the projecting movement of the horizontal bolt 21. To this end, said bolt 16 is provided with a bar portion 70 of substantially 40 square cross-section, slidably extending through the tubular openings 47 in the lock casing 14. The inner end of said portion 70 may be provided with a pin 71.

A flat plate 72 lying substantially against the inner surface of the rear cover plate, is pivoted adjacent one end thereof to the pin 58 projecting from said cover plate. The opposite end of said 50 plate 72 is formed with a small slot 73 slidably receiving said pin 71 therethrough. The plate 72 is likewise formed with a slot 74 receiving the pin 37 fixed to the portion 35 of the horizontal bolt 21. The slot 74 is formed with a portion 76 55 extending radially from the pivot pin 58 and in the retracted position of the horizontal bolt is substantially parallel to the horizontal mid-section of the casing 14. Extending from said portion 76 is another slot portion 77 inclined inwardly toward the horizontal mid-section of the casing; and extending from the other end of the slot portion 77 is a third slot portion 78 likewise extending radially with respect to the pin 58, and in the projected position of the horizontal 60 bolt 21, said slot 78 is disposed substantially parallel to the horizontal mid-section of the casing.

During movement of the horizontal bolt from retracted to projected position, the pin 37 will 70 first move within the slot portion 76 without pivotally moving the plate 72. The pin 37 will then move within the slot portion 77 for causing clockwise pivotal movement of said plate 72 about the pin 58 for projecting the bar 70. The 75 pin 37 will then move into the slot portion 78

which, as shown in Fig. 5 of the drawings, is in horizontal position, without causing any movement of the bar 70. Thus as the U-shaped bolt 25 moves from the position shown in Fig. 4 outwardly, to the position shown in Fig. 5, the vertical bolt 16 is projected downwardly for engagement with the keepers 17 and 20, as will be explained hereinafter. Conversely upon moving the U-shaped bolt 25 from the position shown in Fig. 5 to the position shown in Fig. 4, the vertical bolt 16 is retracted to disengage the same from the keepers 17 and 20.

The construction of the vertical bolt or bar 16 and the strut bolt 19 will now be described. As stated above, the bolt 16 comprises the portion 70 slidably projected into the casing. The lower end of said bar 70 is preferably formed with a cylindrical end portion 80 receiving the upper end of a tubular member 81. Attached to the lower end of said tubular member 81 is a bar 83 substantially similar to the bar 70 and aligned therewith, said bar 83 having a cylindrical projection 84 at the upper end thereof received within the lower end of the tubular member and attached thereto by means of a transverse pin 85, or in any other suitable manner. The tubular member 81 is preferably provided with a longitudinal slot 82 and attached to the door 10 is an angle-shaped member 87 having a finger 88 projecting through the slot 82 and into the tubular member 81. A coiled compression spring 88a housed within the tubular member 81, extends between the finger 88 and the lower end of the cylindrical projection 80. Thus when the bolt 16 which may be made of heavy stock, is projected, the spring 88a will be compressed so that upon retracting said bolt 16, the compressed spring 88a will aid in lifting the bolt 16 so that said bolt as well as the bolts 21 and 25 may be readily actuated by means of the knob or an ordinary key, without the necessity for excessive pressure or strength.

Obviously the casing 14 may have attached thereto or integrally extending therefrom, a suitable projection extending into the tubular member 81 for engagement with the lower end of the spring, to replace the member 87 and its finger 88. The bar 83 preferably extends in the retracted position thereof to substantially the lower end of the door 10. Attached to the door 10 adjacent the lower edge thereof, is a member 90 having a sleeve portion 91 slidably receiving the lower end of said bar 83 for guiding the same. The keeper 17, which may be of ordinary socket construction and may be attached to the floor 50 in any suitable manner, is preferably of square cross-sectional shape for receiving the lower end of the bar 83 upon projecting said bolt 16.

Slidably mounted on said bar 83 is a yoke member 94 having two parallel wall portions 95 and 96 extending on opposite sides of the bar 83 and an interconnecting wall portion 97 contacting the surface of said bar 83 adjacent the door 10. The walls 95 and 96 preferably extend beyond the bar 83, as shown in Fig. 2 of 60 the drawings. Said walls 95, 96 and 97 are formed with a slot 99 having semi-cylindrical end portions 100, for the purpose hereinafter appearing. A pair of set screws 102 screwed to the wall portion 97, serve to attach the member 94 to the bar 83 in any desired adjusted position. The strut bar 19 comprises an elongated rod 105 having a thickened portion 106 forming a surface 107 disposed at an acute angle to the longitudinal axis of said rod 105, for the purpose 65 70 75 80 85 hereinafter appearing. Said thickened portion 106 is further formed with a pair of oppositely extending, cylindrical portions 108 received within the slot 99 and engaged within the semi-cylindrical portions 100 of said slot. The thickened portion 106 is furthermore rounded as at 110 to permit the rod 19 to be rotated about the portions 108 thereof from the full-line position shown in Fig. 2 to the dot-dash position thereof, shown in said figure. Thus in the dot-dash position shown in Fig. 2, the outer end of the rod 105 is received within the socketed keeper 20, upon projecting the bolt 16. Means is provided for retaining the bolt 19 in lifted position against the bolt 16. To this end, said rod 105 is provided with a pair of oppositely extending aligned pins 111. Slidably mounted on said rod 105 is a U-shaped member 113 having side wall portions 114 formed with aligned vertical slots 115 receiving said pin portions 111 therethrough. The walls 114 are further formed with hooked ends 116 adapted to engage within notches 117 formed in the side wall portions 95 and 96 of the member 94. The bolt 19 may, of course, be disengaged from the yoke 94 by merely lifting the member 113 to disengage the hooks 116 from the notches 117. Thus, when the door is unlocked, the bolt 19 may be maintained in a position shown in full lines in Fig. 2 of the drawings. However, before locking the lock 13, the bolt 19 is first swung downwardly and the knob or key then turned for projecting the bolts so that the end of said bolt may engage within the keeper 20.

Upon swinging the bolt 19 upwardly, the fingers 116 will ride on the upper edge portions 116a to lift the member 113, said member again dropping when the bar 105 contacts the bar 83 and the hooks 116 are received in the notches 117.

Means is provided for accurately locating the casing with respect to the edge of the door 10. To this end, the end wall 31 of the casing 14 adjacent the edge of the door is provided at the rear edge thereof with a pair of symmetrically disposed notches or grooves 120. Attached to the door 10 is a plate 121 having an opening 122 therein overlying the hole 123 in the door which receives the key cylinder. Said plate 121 is further formed with two spaced, symmetrically disposed projections, 124, the outer edges 125 of which are aligned. Said projections 124 are adapted to be received within the grooves 120 of the casing 14. The entire plate 121 is adapted to be received within the ledge 14a formed in the rear open end of the casing. The ledge is thus preferably formed deeper than the thickness of the rear cover plate 32 to leave the additional space necessary for the reception of the location plate 121. Once the plate 121 is attached to the door with the outer edges 125 of the projections 124 flush with the outer edge of said door, the casing 14 may be accurately placed on the door so as to properly position said lock for actuation by a key.

It will now be understood that our improved lock may be used with a right hand door or a left hand door. To reverse the lock it is merely necessary to interchange the pivot plates 59 and 72 and to also interchange the bolts 25 and 16. It is for this purpose that the horizontal bolt 21 is formed with two rack portions 38. When used in one position, one of the racks 38 meshes with the pinion 53 and when the lock

is reversed the other rack 38 meshes with the pinion 53. Obviously the lock may be readily disassembled to reverse the bolts. The rear cover plate may be readily removed and the pivoting plates 59 and 72 are readily disengaged from the cover plate and from the horizontal and vertical bolts. Furthermore, the U-shaped bolt 25 as well as the bar 70 may be easily slidably moved out of the slots or openings 46 and 47 upon disengaging the pivot plates 59 and 72. The length of the vertical bolt 16 may be adjusted by cutting off a portion of tube 81. Obviously the strut bolt 19 as well as the yoke 94 may be omitted if desired.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth, or shown in the accompanying drawings is to be interpreted as illustrative and not in a limiting sense.

Having thus described our invention, we claim as new and desire to secure by Letters Patent:

1. In combination with a door, a casing attached to said door with one wall of said casing substantially flush with the edge of said door, and a flat location plate fixed to said door and disposed between said casing and door and having an edge substantially flush with said wall and with the edge of said door.

2. In a lock, in combination, a casing adapted to be attached to a door adjacent the edge thereof, a bolt slidably and rotatably mounted within said casing and projecting therefrom, a bolt extending from the casing and projecting substantially to the lower edge of the door, and means for projecting the second bolt for engagement with a keeper fixed to the floor and rotating said first bolt whereby a portion thereof is moved beyond the edge of the door and causing sliding movement of said first bolt, whereby a portion thereof engages the keeper on a door jamb.

3. In a lock, a casing, an elongated bolt extending into said casing and adapted to project substantially to the lower edge of the door on which the lock is mounted, a member slidably receiving said bolt, means for attaching said member to said bolt in a plurality of adjusted positions, and a strut bolt pivotally attached adjacent one end thereof, to said member, the other end of said strut bolt being adapted to engage a keeper in the floor.

4. In a lock, in combination, a casing, a bolt projecting therefrom and formed with a tubular portion, a member fixed with respect to the casing and projecting into said tubular portion, and a spring interposed between said finger and one end of said tubular portion.

5. A lock comprising a casing, a bar extending therefrom, a member attached thereto, a strut bar pivoted to said member, a member slidably mounted on said strut bar, and means on said last member for engaging the first member for retaining the strut bar in lifted position.

6. In combination, a casing, a bolt extending therefrom, a member attached to said bolt, a strut bar pivoted to said member, a member slidably mounted on said strut bar and having a pin and slot connection therewith, said member being provided with a hook and said first

- member being provided with a notch adapted to receive said hook when said strut bar is pivotally moved against said bolt.
7. In a lock, in combination, a casing adapted to be attached to a door, a U-shaped bolt having a portion slidably received within said casing, and a portion rotatably and non-slidably mounted on said first portion, a second bolt slidably mounted within said casing and extending therefrom, and means for projecting said second bolt into engagement with a keeper on the floor and rotating said rotatable portion of the U-shaped bolt to a position extending beyond the edge of the door, and then slidably moving said portion into engagement with a keeper on the door jamb.
8. In a lock, a casing adapted to be attached to a door, a pair of bolts mounted on said casing, and means for moving said bolts in the same direction, one into engagement with a keeper on the door jamb and the other into engagement with a keeper on the floor.
9. In a lock, in combination, a casing, a horizontal bolt slidably mounted therein, and a pair of vertical bolts slidably mounted in said casing and projecting therefrom, and means for projecting said horizontal bolt and moving said vertical bolts in the same direction by a single operation.
10. In a lock, in combination, a casing adapted to be attached to a door, a horizontal bolt slidably mounted on said casing and adapted to be projected into engagement with a keeper on the door jamb, a vertical bolt slidably mounted on said casing and adapted to be moved into engagement with a keeper on said door jamb, and a second vertical bolt slidably received within said casing and adapted to be projected into engagement with a keeper on the floor, and a strut bolt pivoted adjacent an end thereof to said last bolt, the other end of said strut bolt being adapted to engage a keeper on the floor.
11. In a lock, in combination, a casing adapted to be attached to a door, a horizontal bolt slidably mounted on said casing and adapted to be projected into engagement with a keeper on the door jamb, a vertical bolt slidably received within said casing and adapted to be moved into engagement with a keeper on said door jamb, and a second vertical bolt slidably received within said casing and adapted to be projected into engagement with a keeper on the floor, and means for causing movement of all of said bolts by a single operation.
12. In a lock, in combination, a casing, a pair of bolts slidably mounted within said casing and extending therefrom, and means for moving said bolts in the same direction, said means comprising a pair of members each pivoted within said casing and each engaging one of said bolts, respectively, and means for causing pivotal movement of said pivoted members.
13. In a lock, in combination, a casing, a U-shaped bolt having an arm slidably extending into said casing, and an arm parallel to said first arm and adapted to be disposed beyond said casing, and a second bolt slidably extending into said casing and normally projecting therefrom, and means for moving said second arm of said U-shaped bolt into engagement with a keeper on the door jamb and said second bolt into engagement with a keeper on said floor by a single operation.
14. In a lock, in combination, a pair of bolts mounted on said casing and projecting therefrom, and means for moving one of said bolts into engagement with a keeper on the door jamb, and the other bolt into engagement with a keeper on the floor, said means comprising a member mounted for reciprocation within said casing and having a pair of pins projecting therefrom; a pair of members pivoted within said casing and each having a slot receiving one of said pins, said pivoted members engaging said bolts, and means for slidably moving said reciprocating member for causing pivotal movement of said pivoted members.

IRVING KEMP.
